United States Patent Office.

NICHOLAS S. VEDDER, OF TROY, NEW YORK.

Letters Patent No. 82,897, dated October 6, 1868.

IMPROVEMENT IN COOKING-STOVES.

The Schedule referred to in these Letters Patent and making part of the same.

TO ALL WHOM IT MAY CONCERN:

Be it known that I, NICHOLAS S. VEDDER, of Troy, in the county of Rensselaer, and State of New York, have invented a new and useful Improvement in Cooking-Stoves; and I do hereby declare the following to be a full and correct description of the same, sufficient to enable others skilled in the art to which my invention appertains to fully understand and construct the same, reference being had to the accompanying drawings, which make part of the specification, and in which—

Figure 1 is a top view of my improved stove.

Figure 2 is a vertical longitudinal section.

Figure 3 is a partially-sectional front elevation, and

Figures 4 and 5 detached views of parts of the same.

Like letters of reference indicate corresponding parts in the several figures.

The nature of my invention consists in the construction of a piece of said stove, by means of which an air-channel is formed, which conducts air from under the stove to the air-chamber under the fire-grate and fireplace, so as to prevent scorching in the bake-oven.

Also, in making the rear plate of the air-chamber of the bake-oven removable, to enable the chamber to be cleaned.

A, in the drawings, may represent the front plate of the cooking-stove. B is a plate in the rear of it, which, with the sliding plate C and the bottom plate D of the fireplace, forms an air-chamber, E, to which air is admitted through holes, *a*, in the bottom plate of the stove, and the air-channel *b*, formed by the plate B, which is provided with openings *c*, and the piece F, shown in figs. 2, 3, and 5. This piece F is a hollow, three-sided piece of casting, as shown in fig. 5, and is placed between plates A and B, and under the ash-guide *d*. It consists of two upright pieces, *f*; and the cross-piece *f'*, under which the ash-grate *e* slides, and is thus held in place. *i* are cleats, between which the piece F is held.

G is the ash-pit, to the sides of which are secured beads or projections, *g*, on which the grate *e* rests, (its rear end being under the cross-piece *f'* of the piece F,) and under which the ash-drawer *h* slides, in such a manner that, when the drawer is drawn out, its top edges rest against the projections *g*, and prevent the drawer from tipping. In thus separating the grate from the drawer, it is not necessary to touch the grate, when it is desired to remove the ashes from the drawer.

As the air-chamber E is very apt to get filled with dust and dirt drawn up with the current of air passing through it, to cleanse the same becomes necessary. This is almost impossible when the air-chamber is formed in one piece with the stove-plates. By my improved construction, I am enabled to cleanse it easily, by merely drawing out plate C.

If the air-channel *b* were formed on either plate A or B, it would be more difficult to cast, and also very difficult to fit, but, by forming it by means of piece F, it is not only no trouble to cast, but also necessarily must fit without much trimming. I have found it to be practically a great advantage.

Having thus described my invention, what I claim as new therein, and desire to secure by Letters Patent, is—

1. The piece F, when constructed as and for the purposes herein described.
2. The plate C, forming the air-chamber E, when made sliding, as herein shown and described.

The above specification of my improvement in cooking-stoves signed, this third day of July, 1868.

NICHOLAS S. VEDDER.
